(57) **CLAIM**

The ornamental design for a thermometer and humidity gauge with data record as shown and described.

DESCRIPTION

The file of this patent contains at least one drawing/photograph executed in color. Copies of this patent with color drawing(s)/photograph(s) will be provided by the Office upon request and payment of the necessary fee.

1. Thermometer and humidity gauge with data record

1.1 : Front

1.2 : Back

1.3 : Left

1.4 : Right

1.5 : Top

1.6 : Bottom

FIG. 1 is a front view of a thermometer and humidity gauge with data record embodying our new design; FIG. 2 is a back view thereof; FIG. 3 is a left view thereof; FIG. 4 is a right view thereof; FIG. 5 is a top view thereof; FIG. 6 is a bottom view thereof.

1 Claim, 6 Drawing Sheets

(6 of 6 Drawing Sheet(s) Filed in Color)
